UNITED STATES PATENT OFFICE.

RICHARD E. KRAUSE, OF CLEVELAND, OHIO, ASSIGNOR TO THE KRAUSE CARBURETOR COMPANY, OF CLEVELAND, OHIO, A CORPORATION OF OHIO.

CARBURETER.

1,113,221.

Specification of Letters Patent.

Patented Oct. 13, 1914.

Application filed November 19, 1909. Serial No. 528,856.

To all whom it may concern:

Be it known that I, RICHARD E. KRAUSE, a subject of the King of Sweden, resident of Cleveland, county of Cuyahoga, and 5 State of Ohio, have invented a new and useful Improvement in Carbureters for Internal-Combustion Engines, of which the following is a specification, the principle of the invention being herein explained and the 10 best mode in which I have contemplated applying that principle, so as to distinguish it from other inventions.

My invention relates to carbureters for controlling the supply of explosive mixtures 15 to internal combustion engines, its object being to provide a device of this character which will supply such mixture to the engine so as to produce the highest efficiency and economy of operation of the latter.

20 In order to produce such efficiency, the first requirement is to get from the carbureting chamber of the carbureter an explosive mixture of a certain predetermined character as regards the proportions of fuel and 25 air, and then to maintain this character of mixture independently of the varying conditions of speed and load to which the moving parts of the engine are subjected. The character of such mixture is determined by 30 the relation of the area of the discharge

opening of the fuel nozzle to the area of the air inlet surrounding such nozzle. The area of the air inlet is a factor in determining the velocity of the air entering the carbureting chamber, and the velocity of such air, taken in combination with the area of the 35 discharge opening of the nozzle, determines the amount of fuel discharged from such nozzle, determines the proportion of air to 40 fuel in the mixture, and therefore determines the richness of the mixture. As is well known, this air velocity and hence the richness of the mixture may vary within certain predetermined definite limits without 45 substantially affecting the economical result in the operation of the engine. The character of the mixture must, however, be maintained within these definite limits, in order to effect such economy, and this result can

50 only be obtained by maintaining a definite relationship between the area of discharge from the carbureting chamber and the area of the outlet opening of the carbureter, as determined by the throttle valve. It will 55 therefore be seen that it is necessary, in

order to produce this result, to maintain a predetermined difference of pressure upon opposite sides of the point of discharge from the carbureting chamber. To meet this requirement, therefore, it follows that 60 the area of discharge from the carbureting chamber must be made to vary directly as the area of opening of the outlet, according as such outlet opening is varied by the throttle valve. Furthermore, in order to 65 produce the required economical result, it is necessary that this change of area of the discharge opening from the carbureting chamber be effected automatically, and be governed by the rate of flow of fluid through 70 the opening of the outlet. This is true for the reason that inasmuch as the operator is unable, according to present practice, to determine this rate of flow through the outlet, it would be equally impossible for him to 75 provide the required area of discharge from the carbureting chamber by manual operation, without the aid of delicate measuring instruments, which in automobile practice would be impractical. 80

A further object therefore, of my invention is to provide this automatic variation of area, and said invention consists of means hereinafter fully described and particularly set forth in the claims. 85

The annexed drawings and the following description set forth in detail certain mechanism embodying my invention, the disclosed means, however, constituting but one of various mechanical forms in which the 90 principle of the invention may be applied.

In said annexed drawings: Figure 1 is a plan of a carbureter embodying my invention. Fig. 2 is a vertical axial section taken upon the plane indicated by line II-II in 95 Fig. 1. Fig. 3 is a detail perspective of one of the valves controlling the admission of air into one set of carbureting chambers. Fig. 4 is a horizontal section taken upon the plane indicated by line IV-IV in Fig. 2. Fig. 5 is a vertical axial section taken upon the plane indicated by line V-V, Fig. 1. 100

The casing of the carbureter embodying my invention comprises a main or body portion A, a cap B, and an intermediate portion C. The portion A forms a receptacle for the gasoline, open at the top, and having an opening a at the middle of the bottom to which is connected a drain pipe a', controlled by a valve (not shown), by 110

means of which the contents of the receptacle may be withdrawn, as will be readily understood. A projecting portion A' of the part A forms a side chamber, as shown in Figs. 4 and 5, in which is located the needle valve A². This needle valve controls the usual inlet opening a², through which the gasoline is introduced in the receptacle. The upper end of the chamber A' is closed 10 by means of a screw plug a³ provided with a central vertical bore a⁴, through which the upper end of the needle valve A² projects, and through which such upper end may readily move. This needle valve is 15 controlled in the usual manner by means of a suitable float D, and a lever E, actuated by such float.

The lower part of the body portion A is formed with two lateral extensions A³ 20 A³, Figs. 2 and 4, and in each of the upper walls thereof are provided a plurality of threaded openings a⁵, these openings being three in number on each side, in the device illustrated. Into each such opening is 25 screwed an upwardly projecting fuel nozzle F. The intermediate portion C of the casing is provided with a plurality of carbureting chambers C', corresponding in number with the number of nozzles F, these 30 chambers being provided with lower air inlet openings c c, through which the nozzles project, as shown. Each chamber is furthermore provided with a second air inlet opening c', located at a point above the 35 point of discharge from its respective nozzle. The three openings c' on one side communicate with the cylindrical bore c², and the three on the opposite side communicate with a similar cylindrical bore, the axes 40 of these bores being horizontal, and the bores themselves being formed in a suitable integral extension of the casing, as shown. In each of these bores is located a tubular valve G, each such valve having its two ends 45 open, and being provided in its shell with openings g, which are adapted to register with the openings c'. These valves fit rather tightly in the bores, but are capable of being manually turned about their respective axes, pins g' being provided for 50 this purpose, which pass through a projecting portion of the valve, as shown in Fig. 4. The opposite ends of these valves also project from the casing and split pins 55 g² g² pass through these latter projecting ends, such pins and the pins g' retaining the valve in place, as will be readily understood.

The upper or discharging ends of each 60 carbureting chamber C', with the exception of one, is normally closed by a puppet valve H, the one exception being the middle one of the left hand group of three. Any one of the chambers, however, may be made the 65 exception, as will further appear. These

valves each consist of a main or body portion h and a stem h'. The body portions h vary in thickness and therefore in weight, and the stems extend upwardly into cylindrical recesses or guide-ways b, forming an 70 integral part of the upper portion or cap B of the casing. The upper ends of these guide-ways are provided with small openings b', through which air may be discharged from the space above the upper 75 ends of the valve stems, so as to allow these valves to be readily moved in their guide-ways, as will be understood.

The cap B rests upon the intermediate casing portion C, the latter resting upon the 80 main or body portion A, suitable screws a⁶ securing the cap to the main or body portion A, and thereby securing the intermediate portion between them. The cap B forms a chamber J, in which the valves H are 85 located, and into which each of the carbureting chambers discharges. A hollow boss B' projects upwardly from the middle of the cap, and forms an outlet b². The opening in this outlet is controlled by a 90 manually operable throttle valve K, by means of which such opening may be increased or diminished, as will be readily understood.

The areas of the openings c of the carbureting chambers and of the discharge openings of the nozzles, are designed to produce the required velocities of air and fuel discharged, so as to produce a mixture of the desired richness. The character of this mixture may be varied by adjusting the valves G so as to increase or decrease the amount of air which is permitted to pass through the openings c' from the exterior and above the nozzles. This adjustment is made to suit 95 given conditions under which the engine and carburetor are designed to operate, as will be readily understood. Such adjustment having been made, the device operates 100 as follows: Assuming that the throttle valve 105 has been moved to provide an opening in the outlet of a given area, the engine is started in the usual manner, and a flow of air and gasoline through the carburetor and into the engine cylinders thereby produced. Assuming now that this opening is of an area 110 such that the fluid pressure in the valve-controlled mixing chambers is such as to permit all of the valves to remain in their normal closing positions, a supply of explosive mixture is permitted to enter the chamber J 115 from the one carbureting chamber which is not valve-controlled, and the engine continues to operate with a mixture of a substantially constant character, the flow of the 120 mixture being determined by the difference in pressure upon the opposite sides of the throttle valve K. In case it is now desired to increase the speed or power of the engine, the throttle valve is opened still wider, and a 125 130

greater amount of fluid is thereby caused to flow past such valve. If the additional carbureting chambers were not provided, such increased flow would cause an increase of 5 velocity of the air through the one open carbureting chamber, such as would increase the discharge of gasoline from the nozzle to such an extent as to make this mixture too rich. This does not, however, occur, but on 10 the contrary, as soon as the difference of pressure on the opposite sides of the throttle valve decreases to a certain point, the lightest of the valves *b* immediately opens, and the area of discharge of explosive mixture 15 into the chamber *J* is increased by the area of the discharge opening of the carbureting chamber so uncovered. The velocity of movement of the explosive mixture is therefore checked, and the character of the mixture 20 thus maintained substantially constant. Further opening movement of the throttle valve produces a result similar to that just described, and one after the other of the valves, beginning with the lightest, opens to 25 bring successive carbureting chambers into active operation, thus at all times substantially maintaining a supply of explosive mixture of a constant character to the engine cylinders.

30 It will be readily understood by those skilled in the art that the increase or decrease of the engine's speed caused by a decrease or increase of the load under which such engine is operating, will cause the carburetor to act in a manner similar to that above described.

By providing the guide-ways *b* in the cap *B* open to communication with the atmosphere and also opening the ends of the valve 40 stems to such communication, it will be noted that the effective area of the upper surface of each valve is very materially reduced and the difference in pressure which is exerted upon the upper and lower surfaces 45 of said valves is therefore materially increased. This permits me to make the valve comparatively light in weight and in consequence renders it very much more sensitive to such difference in pressure and allows it 50 to be more easily actuated than would be the case were this feature of the construction omitted.

Having fully described my invention, what I claim and desire to secure by Letters Patent is:—

1. In a carburetor, the combination of a casing provided with a plurality of carbureting chambers; a common chamber into which each of said carbureting chambers 60 discharges; an outlet from said common chamber; a throttle valve adapted to control the opening in said outlet; guide-ways formed in the casing opposite said carbureting chambers and communicating with the atmosphere; and a plurality of inde-

pendently mounted valves each adapted to control the discharge from one of said carbureting chambers, said valves being provided with stems respectively projecting into said guide-ways.

70

2. In a carburetor, the combination of a mixing chamber; a plurality of guide-ways each of which communicates with the atmosphere and with said mixing chamber; a plurality of carbureting chambers opposite said guide-ways and communicating with said mixing chamber; a plurality of independently mounted valves of varying weights each of which is provided with a valve stem projecting into one of said guide-ways, each of said valves being adapted to control the discharge from its respective chamber into said mixing chamber.

75

3. In a carburetor, the combination with a reservoir for holding the gasoline, a mixing chamber arranged above said reservoir and separated therefrom; a series of carbureting chambers communicating at their upper ends with said mixing chamber and at their lower ends with the outside air; nozzles mounted on said reservoir and extending up into said carbureting chambers; the top wall of said mixing chamber being provided with openings in alignment with the openings from the mixing chamber into the carbureting chambers; a series of valves of varying weights in said mixing chamber and arranged so as to close the openings between the latter and the carbureting chambers; each of said valves being provided with a valve stem which extends up into the adjacent opening of said mixing chamber.

80

4. In a carburetor, the combination of a reservoir for holding the gasoline; a mixing chamber arranged above said reservoir and separated therefrom; a series of carbureting chambers communicating at their upper ends with said mixing chamber and at their lower ends with the outside air; nozzles mounted on said reservoir and extending up into said carbureting chambers; a series of valves of varying weights arranged in said mixing chamber so as to close the openings between the mixing chamber and the carbureting chambers, each of said valves being provided with a valve stem; and means in the upper wall of said mixing chamber for guiding said stems.

90

5. In a carburetor, the combination of a reservoir, for holding the gasoline; a mixing chamber arranged above said reservoir and separated therefrom; a series of carbureting chambers communicating at their upper ends with said mixing chamber and at their lower ends with the outside air; nozzles mounted on said reservoir and extending up into said carbureting chambers; and a series of valves of varying weights arranged in said mixing chamber so as to close the open-

100

ings between the mixing chamber and the carbureting chambers, each of said valves being provided with a valve stem; the upper wall of said mixing chamber being provided 5 with guide-ways adapted to receive said stems and in which the latter are adapted to slide, each of said guide-ways being closed and provided with an opening of an area reduced as compared with the area of 10 the stem, each such opening communicating with the atmosphere.

6. In a carbureter, the combination of a main casing portion, formed with a fuel reservoir and open at the top; an intermediate 15 casing portion resting upon said main casing portion, closing the top of the latter, and provided with a plurality of carbureting chambers; a cap casing portion resting upon said intermediate casing portion, and provided 20 with an outlet opening; means for securing said three casing portions to each other; a plurality of fuel nozzles connected with said reservoir, and projecting into said carbureting chambers; a plurality of valves 25 controlling the discharge from said carbureting chambers; and a throttle valve controlling said outlet opening.

7. In a carbureter, the combination of a main casing portion forming a fuel reservoir open at the top; an intermediate casing 30 portion resting upon said main casing portion, closing said reservoir, and provided with a plurality of vertical carbureting chambers; a cap casing portion resting upon 35 said intermediate casing portion, forming a common chamber into which said carbureting chambers discharge, and provided with an outlet opening; a plurality of vertical fuel nozzles respectively projecting into said 40 carbureting chambers; a plurality of valves controlling the discharge from said carbureting chambers; a throttle valve controlling said outlet opening; said carbureting chambers provided with auxiliary air inlet openings; valves for controlling such additional 45 air inlet openings; and means for securing said three casing portions to each other.

8. In a carbureter, the combination of a main casing portion forming a fuel reservoir 50 open at the top; an intermediate casing portion resting upon said main portion, closing said reservoir, and provided with a plurality of vertical carbureting chambers, each having a lateral air inlet opening in its 55 side; a cap casing portion resting upon said

intermediate casing portion, forming a common chamber into which each of said carbureting chambers discharges, and with an outlet opening; a plurality of vertical fuel nozzles communicating with said reservoir, 60 and projecting respectively into said carbureting chambers through the lower air inlet openings thereof; valves for controlling said lateral air inlet openings; a plurality of valves in said common chamber controlling 65 the discharge into the latter from said carbureting chambers; a throttle valve in said outlet opening; and means for securing the said three casing portions to each other.

9. In a carbureter, the combination of a main casing portion forming a fuel reservoir; an intermediate casing portion resting upon said main casing portion, closing said reservoir, and formed with a plurality of vertical tubular carbureting chambers, each 70 such mixing chamber having a lower air inlet opening and an upper discharge opening, together with a lateral auxiliary air inlet opening; a plurality of fuel nozzles connected with such reservoir, and projecting 75 respectively into said mixing chambers through the lower air inlet openings thereof; valves for controlling said lateral auxiliary air inlets; a cap casing portion resting upon said intermediate casing portion, forming a 80 common chamber into which said carbureting chambers discharge, and with an outlet opening; a plurality of valves independently mounted in said common chamber, and controlling the discharge into the latter from 85 said carbureting chambers; means for securing said three casing portions to each other; and a throttle valve in said cap outlet opening.

10. In a carbureter, a casing comprising the combination of a main or body portion forming a fuel reservoir; an intermediate portion formed with carbureting chambers, resting upon said main portion, and closing the top of said reservoir; a cap 90 portion resting upon said intermediate portion, and provided with an outlet; and means for securing said three casing portions to each other.

Signed by me this 17th day of November, 105
1909.
